DESIGN.

J. L. FOLSOM.

CARPET.

No. 15,406.

Patented Sept. 16, 1884.

UNITED STATES PATENT OFFICE

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,406, dated September 16, 1884.

Application filed August 6, 1884. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design is closely filled in with large flower and leaf groups overlying two plain grounds, the darker covering the greater part of the design, and the lighter appearing in places as shown in the photograph. In the

center of the photograph is a large group having several open flowers at its center and projecting fern-sprays on all sides, and a blossom-spray to the left above, and one to the right above. The upper and lower portions of the photograph show a still larger flower and leaf group having three large open flowers, fern-sprays below, clusters of star-shaped flowers above and on the left, and a sprig of moss-rose buds above on the right of the group. Various smaller groups complete the design.

I claim—

The design for a carpet, substantially as shown and described.

JAS. L. FOLSOM.
